ATTORNEYS.

UNITED STATES PATENT OFFICE.

HARRY P. WURMAN, OF BROOKLYN, NEW YORK, ASSIGNOR TO BAYUK CIGARS INCORPORATED, OF PHILADELPHIA, PENNSYLVANIA, A CORPORATION OF MARYLAND.

CIGAR-FINISHING DEVICE.

Application filed April 30, 1925. Serial No. 26,849.

My invention relates to means for finishing cigars, and more particularly to a device for smoothing out and securing the end portion of the wrapper of cigars. In making 5 cigars, the wrapper is applied to the bunch at one end and rolled on spirally, paste being applied to the free or head end of the wrapper to secure it. If the wrapper be applied by hand rolling, care is required to 10 smooth out the end of the wrapper, and it must be subjected to some pressure in order to insure its adherence after the rolling operation is completed. If the wrapper be applied by machine rolling, it is usually necessary to smooth out the end portion of the 15 wrapper, which tends to be wrinkled in the rolling operation, and to apply pressure to it to insure that it be secured by the paste.

While the end of the wrapper may be 20 smoothed out by hand, there has been in use for this purpose a device consisting of a metallic cup-shaped member rotated by suitable means and into which the butt end 25 of the cigar is placed after rolling. The walls of the cup serve to smooth out the end of the wrapper and cause it to adhere to the bunch. However, such a device is of limited advantage and acts only on the extreme end of the cigar.

Now it is the object of my invention to 30 provide a device which will not only smooth out the end of the wrapper and cause it to adhere to the bunch in a superior manner, but which will also smoothly distribute any 35 surplus paste and which will act on the wrapper for a substantial distance from the extreme end and which will result in the production of a cigar of superior appearance and workmanship, whether hand or machine rolled.

Having now indicated, in a general way, the nature and purpose of my invention, I will proceed to a detailed description thereof with reference to the accompanying drawings in which there has been illustrated a 45 preferred embodiment, and in which—

Fig. 1 is a side elevation, partly in section, of a device embodying my invention.

Fig. 2 is a view showing details of the 50 device.

Fig. 3 is a front view of the device shown in Figs. 1 and 2.

a indicates a bracket provided with a bearing through which passes a shaft *b* adapted

to be rotated by any suitable means and 55 centrally bored from its outer end for the reception of a pin *c* on the outer end of which is a cup *d*, the interior of which is formed for the reception of the butt end of a cigar *e*. The pin *c* is made a tight fit in 60 the shaft *b* so that when the shaft is rotated the cup will be rotated with it.

Adjacent the end of the shaft and secured to it by means of a set screw *f* is a collar *g* to which in turn is secured, by means of a bayonet joint *n*, an annular casing *h*. The casing extends about the cup *d* and is provided with an internal flange *i* in line with the outer end of cup *d*. Within the casing and bearing against the flange *i* is a disc *j*, 65 secured by means of screws *k*. The disc is centrally apertured and within the aperture is secured an annular brush *l*. The brush may be of any desired construction and for example may be formed of pile fabric, the 70 back of which is secured to the wall of the aperture by glueing.

Extending from the bracket *a* is a trough-like support *m* for the cigar *e*, which serves as a guide for the cigar, the butt end of which, as will be observed from an inspection of Fig. 1, is inserted through the brush in the aperture in disc *j* and into cup *d*, which, when the shaft *b* is rotated, will act 75 to smooth out and press the end of the 80 wrapper.

It will be noted that in the device embodying my invention the tuck end of the wrapper will be treated by the cup, while the brush will smooth out the wrapper adjacent the end, evenly distribute any paste thereon and press the wrapper into firm adherence with its overlapping convolutes and with the binder on the bunch.

Having now fully described my invention, 85 what I claim and desire to protect by Letters Patent is:

1. A device for finishing cigars comprising 90 an annular brush, the brushing portion of the brush being arranged to surround the cigar to be finished, and means to rotate said brush about the cigar to smooth down the end of the cigar wrapper.

2. A device for finishing cigars comprising 100 an annular brush having brushing elements on its inner periphery, means to limit the extension of a cigar through said brush, and means to rotate said brush.

3. A device for finishing cigars comprising a disc provided with a central aperture, an annular brush within the aperture in said disc, having brushing elements on its inner periphery and means to rotate said disc and brush about the cigar, to cause the brushing elements to smooth the end of the cigar wrapper. 35
4. A device for finishing cigars comprising a disc provided with a central aperture, an annular brush within the aperture in said disc the brushing portion of the brush being arranged to surround the cigar to be finished, means to limit the extension of a cigar through the brush in said disc, and means to rotate said disc. 40
5. A device for finishing cigars comprising a disc provided with a central aperture, an annular brush within the aperture in said disc the brushing portion of the brush being arranged to surround the cigar to be finished, means to limit the extension of a cigar through the brush in said disc, and means to rotate said disc and brush in unison. 45
6. A device for finishing cigars comprising a disc provided with a central aperture, an annular brush within the aperture in said disc the brushing portion of the brush being arranged to surround the cigar to be finished, a cup-shaped element for the reception of the end of a cigar adjacent said brush and concentric therewith and means to rotate said brush. 50
7. A device for finishing cigars comprising a disc provided with a central aperture, an annular brush within the aperture in said disc the brushing portion of the brush being arranged to surround the cigar to be finished, a cup-shaped element for the reception of the end of a cigar adjacent said brush and concentric therewith and means to rotate said brush and said cup-shaped element. 55
8. A device for finishing cigars comprising a rotatable shaft, a cup-shaped element for the reception of the end of a cigar mounted on said shaft, a casing mounted on said shaft and surrounding said cup-shaped element, an annular brush having brushing elements on its inner periphery carried by said casing adjacent to and in line with said cup-shaped element, and means to rotate said shaft. 60
9. A device for finishing cigars comprising a rotatable shaft, a cup-shaped element for the reception of the end of a cigar mounted on said shaft, a collar mounted on said shaft, a casing removably secured to said collar and enclosing said cup-shaped element, a disc having a central aperture in line with said cup-shaped element removably secured within said casing adjacent the end of said cup-shaped element, an annular brush having brushing elements on its inner periphery secured in the aperture in said disc, and means to rotate said shaft. 65

In testimony of which invention, I have hereunto set my hand, at Philadelphia, Pa., on this 27th day of April, 1925.

HARRY P. WURMAN.
